SLIDING CLOSURE HOPPER CLOSURE OUTLET ASSEMBLY

George B. Dorey, Westmount, Quebec, Canada, assignor to Enterprise Railway Equipment Company, Chicago, Ill., a corporation of Illinois

Filed Mar. 16, 1961, Ser. No. 96,244
6 Claims. (Cl. 105—282)

This invention relates to an improved discharge outlet structure for a hopper and relates more specifically to that type of hopper having a discharge opening with a movable gate for controlling discharge of lading such as largely employed for railway hopper cars and the like.

The invention is by way of an improvement on the conventional type of outlet having a sliding gate mounted to slide on horizontally disposed ledges lying in the discharge area. In such structures there is a tendency toward retention of lading on the ledges and, owing to difficulties experienced in effecting proper cleaning of the gates and associated ledges, residual lading generally becomes packed and hardened. The hardened lading hinders the operation of the gate and results in delays and costly cleaning problems arise which penalize consignors and consignees. Furthermore, the frictional resistance incurred when dragging a sliding gate over trackways renders such a system useless with soft metal, such as aluminum.

The instant invention contemplates an improved structure wherein rollers are substituted for the sliding surfaces and wherein lading retaining supporting ledges are largely eliminated from the discharge area and disposed exteriorly of the opening to support the gate at its overhanging end exteriorly of the discharge area. The improvement further contemplates a structure wherein a gate is mounted for tilting movement with mechanism allowing for oscillating movements of the gate for loosening residual lading on the gate as it is moved to closed position.

The objects of the invention among others are: To provide anti-friction rollers on the gate and cooperating trackways for the rollers located beyond the discharge opening; to provide anti-friction rollers adjacent one end of the discharge opening on which the gate is arranged to have tilting movement; to provide a combination sliding and tilting gate with means for controlling the tilting movement of said gate; to provide a link operated movable gate with supporting rollers coaxially located with reference to the pivotal axis of the linkage connecting the linkage and gate; to provide an operating shaft having radially extending arms and linkage connecting the arms and gate and operable to swing the connected end of the gate over and beyond the shaft; to provide a novel mechanical movement for retaining the linkage in folded relation with an operating shaft during rotation of the latter in a direction to close the gate; to provide open ended bearings for receiving an operating shaft when assembled with associated linkages to a gate; and to provide an improved sealing and locking member for retaining an operating shaft in fully toggled relation with a gate.

The invention further resides in certain details of construction and refinement of parts such as pointed out in the specification and shown on the drawings.

For comprehension of the invention reference may be had to the accompanying drawings wherein the improvement is shown as applied to the lower portion of a load containing hopper.

In said drawings,

FIG. 1 is a side elevational view of the lower portion of a load containing hopper showing the improved outlet structure applied thereto, said view showing the gate in closed position and the operating handle being omitted.

FIG. 2 is a plan view of the structure shown in FIG. 1 with the hopper floor sheets and shaft operating handle

2

omitted and certain parts broken away to illustrate better the construction.

FIG. 3 is an end elevational view of FIG. 1 as viewed from right to left.

FIG. 4 is a vertical longitudinal sectional view taken on a line 4—4 of FIG. 2.

FIG. 5 is a vertical longitudinal sectional view similar to FIG. 4 except that the gate is shown in opened position.

FIG. 6 is a vertical longitudinal sectional view similar to FIG. 4 except that the gate is shown with its leading edge withdrawn from its elevated position and its supporting brackets.

FIG. 7 is a vertical longitudinal sectional view similar to FIGS. 4, 5 and 6 except that the gate is shown in position prior to the initiation of its major tilting movement.

FIG. 8 is a vertical longitudinal sectional view similar to FIGS. 4 and 7 inclusive except that the gate is shown in substantially its maximum tilted position.

FIG. 9 is a vertical transverse sectional view taken on a line 9—9 of FIG. 1.

FIG. 10 is a detached plan view of the gate and operating mechanism in assembled relation.

FIG. 11 is a vertical longitudinal sectional side view of the assembly shown in FIG. 10 and taken along the line 11—11 thereof.

FIG. 12 is a fractional vertical sectional view taken on a line 12—12 of FIG. 3.

In said drawings, 10 indicates a four sided hopper formed in part by oppositely sloping longitudinally extending walls 11 and 12 which meet with oppositely extending transversely extending walls 13 and 14 to form the four sides of the hopper. The said four walls lead to a discharge area 15 which is closed by a movable gate 16 as will be described.

The lower portion of the hopper 10 is surrounded by a frame structure 17 which is formed in part by side walls members 18 and 19 which meet at one end of the discharge area 15 with a transverse member 20 and at the opposite end of the discharge area with upper and lower transversely extending members indicated at 21 and 22 respectively. The said members 21 and 22 are vertically spaced to form a slotted opening 23 therebetween through which the gate 16 projects to extend beneath the wall 14 of the hopper 10.

The side members 18 and 19 each include a vertically extending wall section 24 lying outwardly of and adjacent the sides of the gate 16 and an upper sloping wall 25 overlying the related sloping walls of the hopper proper. Similarly the transversely extending wall member 20 includes a vertically extending wall section 26 and an upper sloping wall 27 which overlies the sloping end wall 13 of the hopper. The sloping walls 25 of the side members 18 and 19 and of the transverse end member 20 merge into sloping wall sections 28 which constitute roof like shields extending above the gate 16 when in closed position. The said side members 18 and 19 and transverse member 20 are provided with outwardly extending marginal reinforcing walls 29.

The upper transverse wall member 21 includes a section 30 that overlies the hopper wall 14 and, adjacent the bottom margin of wall 14, it is deflected to present a lower section 31 sloping at a lesser angle than the hopper wall 14. The lower section 31 is reinforced by an angle shaped member 32 having angularly related walls 33 and 34 with wall 33 lying against the under surface of wall section 31 and suitably welded thereto. The adjacent wall 34 extends above the projecting end of the gate 16 when the latter is in closed position as seen in FIG. 4.

The lower transverse end member 22, which extends beneath the gate 16, is preferably in the form of an inverted U having oppositely sloping walls 36 and 37 con-

nected on an arcuate bend 38 of substantial curvature. The ends of the sloping walls 36 and 37 are notched at 39 to receive rollers 40 whereby the gate 16 is supported as will be described.

Side extension members 41—41, which preferably consist of flat plate elements, are spaced laterally outwardly from the side walls 24 and extend lengthwise thereof, as seen in FIG. 2, to a location corresponding substantially to the end of the travel of the gate 16 in an opening direction. The said members 41—41 overlie the walls 24 for an appreciable distance and are inwardly deflected, as indicated at 42—42, and said deflected ends are suitably welded to the walls 24—24 and to the laterally extending reinforcing walls 29—29 of the side wall members 18 and 19.

The gate 16 (FIGS. 10 and 11) is preferably formed of a plate 45 having one end flanged as at 46 and side flanges 47—47 forming therewith a three sided pan shaped member. The flanged end of the gate is fitted with extension brackets 48—48 that are apertured for receiving a rod 49 therethrough. The ends of the rod 49 project beyond the sides of the gate 16. A roller 50 is pivotally mounted on each said projecting end of the rod 49. The brackets 48—48 extend beyond the end of the gate 16 for an appreciable distance and the side flanges 47—47 are extended to overlap said brackets 48—48 and are suitably welded thereto.

The gate 16 in its closed position slopes upwardly from its projecting end to its leading end 51 and this condition is attained by elevating the leading end 51 of the gate 16 as it approaches its closed position as seen in FIG. 4. Here the upper inner corners 53 of the edges 54 of the side flanges 47 contact the under surface 55 of the roof like shielding wall 28 as best shown in FIG. 9. The marginal edges 54 of the side flanges 47 taper from the projecting end to the leading end 51 of the gate 16 a sufficient extent to dispose them along a horizontal level and in close sealing engagement with the under surface 55 when the leading end 51 of the gate 16 is elevated.

The leading end 51 of the gate 16, when in closed position as shown in FIG. 4, seats on brackets 56—56 which have inclined runways 57—57 leading to seats 58—58. The said runways 57—57 ease the leading end 51 of the gate 16 upwardly into seating engagement with the seats 58—58 as the final closing movement of the gate is reached. The trailing or projecting end of the gate 16, when in closed position, is carried by rollers 50 in cooperation with the upper and lower trackways 59—59 and 60—60, said trackways extending inwardly laterally from the side extension members 41. The gate 16, when its leading end 51 is released from its elevated position (FIG. 6) then bears on the rollers 40 and due to the distribution of the loading on the overhanging portion thereof, tilts downwardly about the pivotal axis of rollers 40, thereby exerting an upward thrust on the projecting end of the gate 16. The upward thrust of the projecting end of the gate 16 is arrested by upper trackways 59—59 in cooperation with the rollers 50 which, as will be understood, coat with the undersurface of the trackways 59—59 to control vertical displacement of the gate 16. The lower trackways 60—60 become effective to support the projecting end of the gate 16 thereon during the gate closing operation when the mechanism imparts a downward thrust to the rollers 50.

The means for moving the gate 16 and controlling its tilting movement in cooperation with the trackways 59—59 and 60—60 includes a rotatable shaft 62 journaled in bearings 63—63 disposed adjacent the outer ends of the side extensions 41—41. The shaft 62 includes radially extending arms 64 which preferably consist of flat bars suitably welded thereto to form therewith an integrated structure. Linkages 67—67 pivotally connect at one end with the arms 64—64 and piv-

totally connect at the opposite end with the brackets 48—48 through the medium of the rod 49.

The linkages 67 each consist of a pair of plates 68—68 which straddle the arm 64—64 and the lugs 48—48. Connection between the arms 64—64 and the plates 67—67 is carried out through the medium of pivot pins 69—69 which are retained in position by suitable welding at each end. Each pair of link plates 68—68 are further maintained in spaced relation by suitable welding to the rod 49.

The shaft 62 with its radial arms 64—64 is arranged for assembly with the gate 16, FIGS. 10 and 11, prior to its installation in the frame structure 17 and to this end each bearing 63, FIG. 12, presents an open end to permit ready installation or removal of the gate assembly. Each bearing 63 preferably consists of a plate bent into a U-shape with a semi-circularly shaped end portion 72 merging into upper and lower flat wall sections 73 and 74. The bearings 63—63 are applied to the frame structure 17 by suitably welding the same to the extension plates 41. The shaft 62 is held in position in the bearings 63—63 by blocking members 76 which are formed with an arcuate face 77 for registering with the arcuate surface of the shaft 62. The blocking members 76—76 are retained in place by suitable cotter pins 78—78 which extend through the upper and lower flat wall sections 73 and 74. The shaft 62 is provided at one end with an operating head or handle 79 having a pair of opposed openings 80 for the reception of an operating bar 81.

The gate 16 is retained in closed position by the arms 64—64 and linkages 67—67 which straighten out and swing slightly over a dead center line 82 connecting the axes of shaft 62 and rod 49, as will be observed by reference to FIG. 4, to a toggle locked position. To positively retain the mechanism in its toggle locked position there is provided a lug 83 suitably welded to the shaft 62 and cooperable therewith is a pawl 85. The pawl 85 preferably consists of a plate like member sandwiched between a pair of bracket plates 86—86, FIG. 2, and pivotally connected thereto by pivot pin 87 which extends at substantially a right angle to the shaft 62 thereby forming a stop preventing rotation thereof. The bracket plates 86—86 are suitably welded to and extend laterally outwardly from the adjacent side extension member 41. The lugs 83 and pawl 85 are provided with apertures 88 and 89, as shown in FIG. 3, which are arranged to be brought into registering relation for the accommodation of a sealing ribbon 90.

The mounting of the rollers 40 is preferably through the medium of a rod 91 which is rotatably mounted to extend at its ends through the vertical wall sections 24—24 of the frame structure 17 and through the extension wall members 41—41. The rod 91 is maintained against axial displacement by stop plates 92—92 welded to the walls 29.

The shaft 62 is maintained in axial alignment in its bearings 63 in one direction by the lug 83 and in the opposite direction by a head 93.

The upper trackways 59—59 includes arcuate extensions 94—94 having arcuate under surfaces 95—95 contoured to follow the path of the rollers 50 throughout the swinging movement of the connected end of the gate 16 and to this end the arcuate surfaces 95—95 are concentrically related to the axis of rotation of the shaft 62. As seen in FIGS. 4—8 each side extension member 41 has an upwardly projecting portion 41a the ends of which overlie and are suitably welded to the end portions of the arcuate extension 94 associated therewith. The frame structure 17 is tied crosswise by means of an angle shaped member 96 which also constitutes a stop for limiting movement of the arms 64—64 when the gate 16 is in closed position.

Grooves 97 and 98 are provided on the underside of the frame structure 17 for receiving a discharge chute (not shown). The groove 97 is formed between the un-

derside of one of the walls 29 and a plate 99, FIG. 9, spaced therefrom while the groove 98 is formed between the underside of the wall 36 and a flange of an angle shaped member 100, FIG. 8, suitably welded to the wall 36.

The operation of the mechanism and the advantages thereof may be best realized by considering the sequence of movement involved in one opening and closing closing cycle of the gate 16. Assuming the gate 16 in closed position with the arms 64-64 and linkages 67-67 in straightened toggle locked position as seen in FIGS. 1 and 4, the pawl 85 is swung to an overbalance released position as indicated by conventional dot and dash lines in FIG. 3. The operator inserts the bar 81 in one of the sockets 80 of the operating head 79 and by a partial rotation of the shaft 62 in a clockwise direction, as viewed in FIG. 4, effects a break in the toggle locked relation of the arms 64-64 and linkages 67-67. Continued rotation of the shaft 62 in the indicated direction moves the gate 16 a sufficient distance to dislodge the leading end 51 from the seats 58-58 and allows it to drop away from the lading to the position shown in FIG. 6. The gate 16 then balances on the carrying rollers 40-40 and swings the projecting end upwardly with the gate rollers 50-50 in contact with the under surfaces of the upper trackways 59-59. Upon further rotation of the shaft 62 the gate 16 moves outwardly in a substantially horizontal plane until such time as the linkages 67-67 fold to seat on the shaft 62 as seen in FIG. 7. With the linkages 67-67 seated on the shaft 62 they and arms 64-64 now operate as radial arms as the clockwise rotation of the shaft 62 continues. The connected end of the gate 16 is swung upwardly in an arcuate path, meanwhile tilting around the supporting rollers 40-40 as seen in FIG. 8 with the rollers 50-50 engaging and being guided by arcuate surfaces 95-95 on the arcuate extensions 94-94. As the rotation of the shaft 62 continues, the connected end of the gate 16 is swung over and across the plane of the shaft 62 to rest thereon in fully opened position, FIG. 5.

The closing operation of the gate is a reversal of the opening movement with the rollers 50-50 contacting the under surfaces 95-95 of the arcuate extensions 94-94 to maintain the linkages in folded relation until such time as the gate 16 again assumes the substantially horizontal position, FIG. 7, and thereafter the said rollers 50-50 roll along the lower trackways 60-60.

The up and down movement of the projecting end of the gate 16 as it is moved across the plane of the shaft 62 jars the gate 16 to shake loose any residual lading adhering thereto.

What is claimed as new is:

1. In combination:

- (a) an outlet assembly for a hopper having a discharge opening and a movable gate for said opening,
- (b) means mounting said gate on said outlet assembly for translatory movement from and to closed position,
- (c) means for moving said gate in a closing direction and an opening direction including a shaft rotatably mounted on said outlet assembly in lateral spaced relation to said gate when closed and below its path of movement and having radially extending arm means and linkage pivotally connected at one end to said arm means and at the opposite end to said gate,
- (d) said linkage being foldable to seat on said shaft and rotatable therewith to lift the end connected to said gate over and beyond said shaft upon rotation of said shaft to open said gate, and
- (e) means for retaining said linkage in folded relation on said shaft during rotation of said shaft to move said gate from open position toward closed position comprising trackway means on said outlet assembly concentrically disposed with respect to the axis of rotation of said shaft for reacting against said link-

age at the end of said gate to which said linkage is connected.

2. The invention as set forth in claim 1, wherein the arm means includes a pair of arms in spaced relation on the shaft, the linkage includes link means individual to each arm, and the reaction of the trackway means is through the pivotal connections between the link means and the gate.

3. In combination:

- (a) a hopper having a discharge opening and a slidable and tilting gate for said opening,
- (b) a frame structure mounted on said hopper bordering said opening and including upper and lower sections disposed above and below said gate respectively,
- (c) said upper section having walls overlying said hopper and said lower section including side walls meeting with transversely extending walls to form a four sided enclosure,
- (d) one end of said gate in its closed position extending over and projecting beyond one of said transverse walls,
- (e) supporting trackways for said gate extending lengthwise from said frame structure outwardly beyond said one transverse wall,
- (f) rollers carried by the projecting end of said gate and guided by said trackways,
- (g) other rollers carried by said one transverse wall in spaced relation to the first named rollers and supporting said gate for translatory and tilting movement, and
- (h) means for moving said gate and controlling its tilting movement including:
  - (1) a shaft carried by said frame structure in lateral spaced relation to said gate when closed,
  - (2) radially extending arms rigidly mounted in spaced relation on said shaft, and
  - (3) links pivotally connected at one end to said arms and at the other end to said projecting end of said gate,
  - (4) said arms and links operating as toggles to maintain said gate in closed position.

4. In combination:

- (a) an outlet assembly for a hopper having a discharge opening and a longitudinally movable gate for said opening,
- (b) means on said outlet assembly supporting said gate for movement between closed and open positions,
- (c) said gate in closed position projecting at one end beyond said opening,
- (d) support means extending laterally from opposite sides of said hopper beyond said one end of said gate in closed position,
- (e) bearings supported on the distal ends of said support means,
- (f) a shaft journaled in said bearings,
- (g) arms extending radially from said shaft in spaced relation,
- (h) linkage pivotally interconnecting said arms and said projecting end of said gate with the pivot axis between said arms and said linkage passing through the path of movement of said gate during a portion of its movement between open and closed positions,
- (i) said bearings being open at one side to permit side-wise insertion and removal of said shaft when in assembled relation with said gate, and
- (j) blocking means closing off the open sides of said bearings.

5. The invention as set forth in claim 4, wherein the blocking means include blocking members having concave bearing faces overlying the arcuate surface of the shaft.

6. The invention as set forth in claim 3, wherein the trackways have sections concentrically disposed with respect to the axis of rotation of the shaft, and the rollers

on the projecting end of the gate react against said concentric sections of said trackways when said shaft is rotated to move said gate from open to closed position.
